Heidrich & Company
ATTORNEYS.

UNITED STATES PATENT OFFICE.

WILLIAM I. WEAVER, OF CAMDEN, NEW JERSEY.

PADDING FOR THE COVERING OF FLATWORK IRONERS.

Application filed July 21, 1921. Serial No. 488,621.

To all whom it may concern:

Be it known that I, WILLIAM I. WEAVER, a citizen of the United States, residing in the city and county of Camden, State of New Jersey, have invented a new and useful Padding for the Covering of Flatwork Ironers, of which the following is a specification.

In flat work ironers wherein an endless apron is employed to effect the propulsion and ironing of flat work, it is essential and desirable to employ in conjunction with such endless apron, a sheet of padding or textile fabric for the purpose intended, which should possess certain characteristics, since it is essential that the inner plies of the fabric be loosely bound so as to form a spongy core while the outside plies must be more firmly bound and yet at the same time 20 so woven as to permit an easy flexure of the fabric as a whole, which must have sufficient strength to resist any tensile strains to which it may be subjected in use in passing over the rolls or calenders of the flat work ironer.

To the above ends my invention consists of a novel construction of multiply padding or fabric in which the layers or plies of the fabric are so joined, that the outer plies 30 of the fabric will be firmly bound, while the inner plies will be less firmly bound so as to form a spongy core or interior, thereby producing a fabric or padding which is especially adapted to the purpose named.

For the purpose of illustrating my invention, I have shown in the accompanying drawing a form thereof which is at present preferred by me, since it will give in practice satisfactory and reliable results, although it is to be understood that the various instrumentalities of which my invention consists can be variously arranged and organized and that my invention is not limited to the precise arrangement and organization of these instrumentalities as herein shown and described.

Figure 1 represents on an enlarged scale, a sectional view of the padding or cover for flat work ironers, embodying my invention.

Figure 2 represents a diagrammatic view of the weave diagram employed.

Similar numerals of reference indicate corresponding parts.

Referring to the drawings, In carrying out my invention, I have des-

ignated the warp threads from top to bottom of my novel fabric as A, B, C, D, E, F, G and H and the filling or wefts between said warps, as 1 to 18 inclusive, the position of said filling with respect to the warps being readily understood from the drawings, the fillings 1, 5 and 18 being positioned between the warps G and H. The filling 2 is positioned between the warps E and F.

The fillings 3, 10 and 15 are positioned between the warps A and B. The filling 4 is positioned between the warps D and F. The fillings 6 and 8 are positioned between the warps H and F. The filling 7 is positioned between the warps G and F. The filling 9 is positioned between the warps C and D. The fillings 11 and 13 are positioned between the warps A and C. The filling 12 is positioned between the warps C and B. The filling 14 is positioned between the warps E and F. The filling 15 is positioned between the warps E and F. The filling 16 is positioned between the warps D and E. The filling 17 is positioned between the warps D and C.

It will be apparent from the foregoing that the fillings 1 and 2, 3 and 17, 4 and 5, 9 and 10, 8 and 12, 14 and 18 and 15 and 16 are positioned in substantially vertical alignment.

The filling 7 is in staggered position with respect to the fillings 6 and 8, and the fillings 8 and 12 are in staggered position with respect to the fillings 11 and 13.

It will be apparent from the foregoing that a four ply fabric constructed in accordance with my invention will have the outer plies firmly bound together while the inner plies will be less firmly bound, so as to form a spongy core or interior especially adapted for the purpose stated.

It will be understood by those skilled in the art that the weaving operation to produce my novel fabric is effected by a certain arrangement of the rolls on the pattern chain, which, per se, form no part of my present invention, which relates solely to the novel fabric or padding which I have produced.

It will be evident to those skilled in the art that in my novel fabric or padding, the outside plies are firmly bound, while the inner plies are less firmly bound, forming a comparatively spongy core having the requisite tensile strength, the whole padding,

while having a certain amount of stretch and give, being very resilient, whereby the fabric as a whole will possess the requisite strength and at the same time being capable of being readily bent or flexed. It will be further apparent that in my novel multiply fabric having interlocked or interwoven plies, the wefts or filling are fluffy being of soft spun cotton or the like, while the warps 10 are relatively small in size whereby a novel, soft, multiply padding fabric is produced in which a soft spongy core or inner ply is present.

I am aware that changes may be made in 15 practicing this invention by those skilled in the art, since it is evident that the plies of the fabric may be increased or diminished or otherwise associated to form a fabric resulting in the principles of my invention.

20 Claims:

1. As a new article of manufacture, a soft multi-ply padding fabric having interwoven superposed plies comprising relatively small spaced hard twisted warps and relatively 25 large spaced soft sliver-like interwoven wefts forming a yielding spongy mass, the warps being arranged to firmly bind the outer plies and to less firmly bind the inner plies, several of the warps extending from 30 one ply to an adjacent one thereby serving as binder warps for said plies, and most of

the wefts of the upper plies being staggered relatively to the wefts of the lower plies.

2. A soft multi-ply padding fabric having a series of superposed layers of relatively 35 large soft sliver-like wefts interwoven with a series of relatively small spaced hard twisted warps to form a yielding spongy mass, the lowermost pair of the warp series being twisted around groups of the lower 40 layer of wefts and between these groups being intertwined with certain wefts of the lower layer and adjacent wefts of the layer immediately above the lower layer, the uppermost pair of the warp series being twisted around groups of the upper layer of wefts and between these last mentioned groups being intertwined with certain wefts of the upper layer and adjacent wefts of the layer immediately below the upper layer, the intermediate series of warps being passed over and under the wefts of the intermediate layers, and all of the warps being arranged to firmly bind the upper and lower layers of wefts and to less firmly bind the intermediate layers of wefts. 50

3. A padding fabric as claimed in claim 2 in which most of the wefts of the upper layers are staggered relatively to the wefts of the lower layers.

WILLIAM I. WEAVER.
